UNITED STATES PATENT OFFICE

121,692

DESIGN FOR A COMBINED PERFUME HOLDER AND BASE THEREFOR

Albert Mosheim, New York, N. Y.

Application May 13, 1940, Serial No. 92,324

Term of patent 14 years

To all whom it may concern:

Be it known that I, Albert Mosheim, a citizen of the United States and a resident of New York city, in the county of New York and State of New York, have invented a new, original, and ornamental Design for a Combined Perfume Holder and Base Therefor, of which the following is a specification, reference being had to the accompanying drawing, forming a part thereof.

perfume holder and base therefor showing my new design; and

The dominant features of my design reside in the parts shown by solid lines on the drawing.

I claim:

The ornamental design for a combined perfume holder and base therefor, substantially as shown and described.

ALBERT MOSHEIM.
